James F. Williamson

UNITED STATES PATENT OFFICE.

ARTHUR MARKESON, OF LA SALLE, MINNESOTA.

AUTOMOBILE HEATER.

Application filed May 11, 1923. Serial No. 638,182.

My invention has for its object to provide a simple, but highly efficient heater for an automobile, utilizing the heat from the exhaust manifold.

5 A more specific object is to utilize the air within the back portion of the engine hood, which has already been heated by the engine to some degree.

10 A further object is to provide such a device having a means for warming simultaneously the feet of both the driver and occupant of the seat next to his.

15 To these ends generally stated, my invention consists of the novel devices and combinations of devices hereinafter described and set forth in the claims.

20 My invention, in its preferred form, is illustrated in the accompanying drawings, wherein like notations refer to similar parts throughout the several views, and, in which

Fig. 1 is a side elevation of a part of the front portion of an automobile, partly broken away, showing my improved heater applied for usage thereon;

25 Fig. 2 is a vertical section taken on the line 2—2 of Fig. 1;

Fig. 3 is a vertical section taken on the line 3—3 of Fig. 1;

30 Fig. 4 is a similar view taken on the line 4—4 of Fig. 1; and

Fig. 5 is a plan view, partly broken away, of my heat distributing means.

35 The numeral 6 designates the hood of an automobile of common type, 7 the engine, 8 the fan, 9 the foot-boards, 10 the dash-board, 11 the foot pedals and 12 the exhaust manifold.

40 An elongated casing 13, preferably constructed of sheet metal and for most of its length of U-shaped cross section, encloses the top of the manifold 12 and is snugly secured at its lower edges about the sides of the same. Its open front or receiving end 13^a is directly behind the fan 8 and 45 adapted to receive a current of air from the fan when the engine is running, while its rear or delivery end is diminished into an outlet neck 14, which telescopes into the receiving neck 15 of a heat distributing means 50 to be later described. The casing 13 is equipped at its ends 13^a and 14 with the valves 16 and 17 controlled by the operating rods 16^a and 17^a, which are connected to the valves and extend through the dash-board 55 10 where the ends are equipped with suitable handles located for the driver's ready ma-

nipulation. An auxiliary casing 18 also of U-shaped construction is superimposed on the main casing 13 snugly fitting the same, having its front end secured tightly against the front 13^a of the main casing and having its rear end located within the back portion of the hood 6 and near the rear end of the manifold 12 and held in spaced relation from the rear end 14 of the main casing. The auxiliary casing thus co-operates with the main casing 13 to form a chamber open at the rear end and closed at its front end and diminishing uniformly in height throughout its length. This chamber so formed in the casing 18 is connected to the intermediate portion of the main casing 13 by means of an opening 19 in the top of the casing 13. In making this opening 19, the casing is cut or punched on three sides leaving the front side uncut, so that the cut portion may be bent downward somewhat, to form a guard lip 20, the purpose of which will subsequently be explained.

55 The heat distributing means, previously spoken of includes a foot warming casing 21, preferably constructed of some thin heat conducting material, which rests on the foot boards 9 of the automobile at the side of the foot pedals 11 and, as stated, is connected to the delivery end of the main casing by its telescoping neck 15. Within this casing 21, as shown in Fig. 5, adjacent the neck 15 is a curved deflector plate 22 adapted to force the hot air admitted to circulate throughout the casing and heat the same. At the end of the casing 21 adjacent the driving pedals is a delivery opening 23 directing the hot air on and about the feet of the driver. The current of heated air, therefore, is guided or deflected to the opposite side of the casing before it is delivered onto the driving pedals, thus permitting the casing to become thoroughly heated from the passing air.

60 When the motor is running and the valves 16 and 17 are open, a main current of air will be set up through the main casing. This current will be drawn from the cold air passing through the radiator and the valve 17 will be adjusted to sufficiently restrict the opening at the forward end of the main casing to admit only enough air to set up a main circulation adequate to draw or induce an auxiliary current through the casing 18. Casing 18 receives air preferably from beneath the rear portion of the hood where the air is more or less warmed over the rear end

of the manifold and the rear portion of the engine. Thus a large amount of the air passing over the heated manifold has already been heated to some extent. In the 5 passage over the main casing the comparatively warm auxiliary current is heated somewhat by the radiation from said main casing and is introduced into the main current at an intermediate portion of main casing 18. The main casing delivers at its rear end to the foot warming casing and delivery apparatus 21.

The objection to most forms of manifold automobile heaters is that too large a circulation of cold air is set up through the casing taken adjacent the radiator and consequently the heat from the manifold will not be sufficient to warm this large amount of cold air forced through the casing at a high 10 rate of speed. Applicant is able to set up a restricted flow of air taken from adjacent the radiator and an auxiliary current taken from a relatively warm area whereby the main current will not only flow considerably 15 slower, but will be comparatively warm before passing over the manifold.

Depending lip 20 materially assists in causing a strong induced current through auxiliary casing 18, by lessening the upward 20 pressure of the main current as it passes the opening 19.

The foot warming casing 21 thus acts as a heat reservoir for the use of the feet of a passenger, while the driver's feet are also 25 kept warm by the current of hot air directed on and about the driving pedals. This escaping hot air is then free to circulate within the automobile or inside of a robe, if one is used.

40 The applicant, in actual usage, has found the induced current of air taken within the rear portion of the hood to be remarkably efficient for quickly supplying a large amount of heat. By experience, he has 45 found that with his improved device, he can in five minutes get a certain degree of heat discharged, while without the induced current it takes fifteen minutes to gain the same temperature.

50 The two valves 16 and 17 at opposite ends of the main casing permit the heater to be very satisfactorily adjusted. The valve 17 at the front end of the casing regulates the current forced through by the fan 8, while 55 the smaller valve 16 at the rear of the main casing 13 directly controls the amount of heated air admitted to the distributing means.

60 The auxiliary casing 18, besides effecting the induced current of air, also provides an insulated protective covering for the main casing 13. Thus the main casing is well shielded from the current of cold air expelled by the fan 8.

It will, of course, be understood that various changes may be made in the form, details and arrangement of parts without departing from the scope of the invention. 65

What is claimed is:—

1. An automobile heater including an open ended casing adapted to be disposed on the exhaust manifold of an automobile having its delivery end in communication with the interior of said automobile and having a relatively restricted receiving end disposed 70 adjacent the fan of said automobile whereby a restricted current of comparatively cool air may be set up in said casing and a passage extending forwardly along the side of said casing and communicating at its forward end with the interior of said casing, the rear end of said passage being open to introduce heated air from beneath the hood of said automobile into the current of air through said casing. 75

80 2. An automobile heater comprising an open-ended casing adapted to be disposed on the exhaust manifold of an automobile having its delivery end in communication with the interior of said automobile and having a relatively restricted receiving end disposed adjacent the fan of said automobile whereby a restricted main current of comparatively cool air may be set up in said casing, and an auxiliary casing communicating with said main casing and having its receiving end disposed to receive comparatively warm air about a comparatively warm portion of the automobile whereby a current of comparatively warm air will be introduced into said main current. 90

95 3. An automobile heater comprising an open-ended casing adapted to be disposed on the exhaust manifold of an automobile having its delivery end in communication with the interior of said automobile and its receiving end disposed adjacent the fan of said automobile, means to partially close the receiving end of said casing whereby a restricted current of comparatively cool air 100 may be set up therein, and an auxiliary casing embracing the main casing and forming therewith a chamber with a closed end and an open receiving end disposed within the rear portion of the automobile hood, said 105 chamber communicating with said main casing whereby a current of comparatively warm air will be introduced into said main casing through said auxiliary casing. 110

115 4. The structure set forth in claim 3, said main casing having an opening therein communicating with the interior of said auxiliary casing and a depending deflecting lip disposed forwardly of said opening and extending downwardly and rearwardly. 120

125 In testimony whereof I affix my signature.

ARTHUR MARKESON.
